UNITED STATES PATENT OFFICE.

HEINRICH BOLTSHAUSER, OF ZURICH, SWITZERLAND.

CONDENSING STEAM LOCOMOTIVE.

Application filed May 13, 1922. Serial No. 560,607.

To all whom it may concern:

Be it known that I, HEINRICH BOLTSHAUSER, citizen of the Republic of Switzerland, residing at Hardturmstrasse 19, Zurich,

5 Switzerland, have invented certain new and useful Improvements in Condensing Steam Locomotives, of which the following is a specification, reference being had therein to the accompanying drawing.

10 This invention relates to a condensing steam locomotive fitted with a circulation pump for the cooling water for the condenser and provided with a preheater heated by the exhaust steam of a steam engine 15 driving said circulation pump, and it has for its object to simplify such an arrangement and to render its operation economical. The invention consists in the provision of a pump adapted to draw condensed water as 20 well from the condenser as from the pre-heater and force it into the boiler of the locomotive.

The accompanying partially diagrammatic drawing exemplifies constructions of 25 the invention.

Fig. 1 shows in side elevation with some of the parts in section a steam turbine locomotive provided with a surface condenser, and

30 Fig. 2 shows a modification of a detail.

The driving turbine 1 of the locomotive is supplied with steam from the boiler through a pipe not shown. The exhaust steam from the said turbine reaches a surface condenser

35 2 the cooling water of which is circulated by a pump 4 driven by an auxiliary turbine 3, the condensing water entering the condenser 2 through the pipe 5 and leaving it through the pipe 6. Water is supplied to the pump

40 4 through a pipe 7. The exhaust steam of the auxiliary turbine 3 flows into a pre-heater 8 for the boiler feed water. A piston pump 10 is driven by the auxiliary turbine 3 through the gear 11, 12. Condensed water

45 from the surface condenser 2 is drawn through a pipe 13 by the right hand side of the piston of the pump 10 which draws condensed water out of the preheater 8 through a pipe 14 with the left hand face of its pis-

50 ton. The condensed water drawn through

the pipes 13 and 14 is forced together by the pump 10 through a pipe 16 into the pre-heater 8 and thence pumped to the steam boiler through a pipe 15.

Thus a single pump 10 is used to supply 5 the steam boiler with feed water from the surface condenser 2 and the preheater 8. This arrangement has the advantages of being very simple, easy to handle and smooth in its working and it requires moreover but 60 a comparatively small amount of power to run it.

Since the piston pump 10 absorbs only a small fraction of the power required to operate the cooling water circulation pump 4, 65 the number of revolutions of the group formed by the apparatus 3, 4 and 10 is altered but to an unimportant extent when the pump 10 runs idle. Thus the said pump 10 may run continuously, the result being that 70 there no longer exists the danger of flooding the surface condenser 2 or the pre-heater 8, as is the case in arrangements in which the condenser and pre-heater are each connected to a separate pump which becomes operative 75 only when a definite quantity of condensed water is present.

As is shown in Fig. 2 the two products of condensation delivered by the pump 10 may be forced separately into the pre-heater 8 80 and caused to mix only in the latter from where they are then forced together into the boiler. In Fig. 2 the pipe 16 of the first constructional example is replaced by two pipes 17 and 18.

I claim:

1. A condensing steam locomotive comprising a circulation pump for the cooling water for the condenser, a steam power engine arranged to drive the circulation pump, 90 a pre-heater heated by the exhaust steam of said engine, a pump driven by said steam power engine driving the circulation pump and arranged to draw through separate pipes condensed water from the condenser 95 and also from said pre-heater and force said water through said pre-heater into a boiler.

2. A condensing steam locomotive, comprising a circulation pump for the cooling water for the condenser, a steam power en- 100

gine arranged to drive the circulation pump, a preheater heated by the exhaust steam of said steam engine, and a piston pump driven by said steam power engine one side of said pump communicating with a collecting space for condensed water of the condenser and the other side of said pump communi-

cating with a collecting space for condensed water of the preheater, all the condensed water drawn into the pump being forced ¹⁰ through the preheater into the boiler of the locomotive.

In testimony whereof I affix my signature.
HEINRICH BOLTSHAUSER.
